CLAIM

The ornamental design for a dust mite controller, as shown and described.

DESCRIPTION

1. Dust mite controller

1.1 : Front

1.2 : Back

1.3 : Left

1.4 : Right

1.5 : Top

1.6 : Bottom

1.7 : Perspective

1.1 is a front elevation view of a dust mite controller showing our new design; 1.2 is a back elevation view thereof; 1.3 is a left side elevation view thereof; 1.4 is a right plan view thereof; 1.5 is a top plan view thereof; 1.6 is a bottom plan view thereof; and 1.7 is a perspective view

(Continued)

thereof; besides, the dust mite controller incorporating the new design is mainly used for killing mites, vacuuming, etc.
